E. C. BLOMEYER

WASHABLE GARTER

Filed April 27, 1925

INVENTOR
E. C. BLOMEYER
BY *Munn & Leo*

ATTORNEYS

UNITED STATES PATENT OFFICE.

EDWARD CHARLES BLOMEYER, OF KANSAS CITY, MISSOURI.

WASHABLE GARTER.

Application filed April 27, 1925. Serial No. 26,268.

To all whom it may concern:

Be it known that I, EDWARD CHARLES BLOMEYER, a citizen of the United States, and a resident of Kansas City, in the county 5 of Jackson and State of Missouri, have invented a new and useful Improvement in Washable Garters, of which the following is a full, clear, and exact description.

My invention relates to improvements in 10 washable garters, and it consists in the combinations, constructions, and arrangements herein described and claimed.

An object of my invention is to provide a 15 garter which may be washed and which will remain substantially unaffected by the washing process as distinguished from garters having elastic portions with rubber therein.

A further object of my invention is to 20 provide a device of the type described in which a loop is used with means for enlarging or contracting the loop as desired so as to afford a ready means of inserting a portion of the garter therethrough, while insuring a snug and comfortable fit.

25 A further object of my invention is to improve washable garters of the type herein disclosed, as far as facility of adjustment and the absence of certain buttons or other fastening devices that are found in garters 30 of this type, whereby the construction is rendered simple, and the cost is reduced but without sacrificing the features of comfort and ease of adjustment which are so highly desirable.

35 Other objects and advantages will appear in the following specification, and the novel features of the invention will be particularly pointed out in the appended claims.

40 My invention is illustrated in the accompanying drawings, forming part of this application, in which—

Figure 1 is a view of the garter as extended before it is arranged into a loop for wearing,

45 Figure 2 is a view of the reverse side of the garter,

Figure 3 is a view showing the manner in which the loop is formed,

50 Figure 4 is a view showing the position of the garter in use,

Figure 5 is a view showing a metal slide, and

Figure 6 is a view of a modified form of the device.

55 In carrying out my invention I provide a

body portion 1 which is preferably made of knit goods to provide a certain amount of flexibility or elasticity. Near one end is a substantially triangular portion 2 having reinforcing material stitched to provide a 60 strong end portion to which the strap 3 which carries the clasp 4 is secured. This clasp 4 is of the ordinary type, consisting preferably of a metal loop and rubber covered lug.

The opposite end of the garter has a portion 5 which is shown in the drawing as reinforced with some non-flexible fabric for the purpose of preventing the slots 6 and 7 from spreading. It is to be understood, 70 however, that the portion 5 would not necessarily need to be so reinforced, should the garter be made of a heavier fabric, knit or otherwise.

Disposed on the body portion of the garter 75 is a slide 8 of the shape shown in Figure 3. This is a piece of metal having parallel slots 9 separated by a bar portion 10. It will be noted that one side of the slide is prolonged as shown at 11 for a purpose hereinafter 80 explained.

From the foregoing description of the various parts of the device, the operation thereof may be readily understood. The metal slide 8 is placed on the body portion 85 by threading the same through the slots 9. In order to form a loop, the end of the garter having the clasp 4 (see Figure 3) is folded back and passed first through the slot 6 to one side, and then through the slot 7 to the 90 opposite side, thus forming a loop portion 12. The slide 8 determines the size of the loop 12, since it cannot pass through the slot 6. The extended portion 11 in fact overlies the slot 6, for the purpose of preventing one end of the slide from working into the slot in case one end should be in advance of the other. By moving the slide 8, the size of the loop may be regulated.

The garter thus formed is now ready for 100 use, and in using it, it is passed around the leg and then the end bearing the clasp 4 is drawn through the loop 12 and fastened to the sock. The garter then has the position shown in Figure 4. The elasticity of the 105 body portion renders the garter comfortable to wear and yet holds it to the leg so that there is no danger of its becoming loose and slipping down. The metal slide 8, it will be observed, while determining the size of 110

the loop, determines the effective length of the garter, and it can be readily adjusted to fit.

I am aware that garters of this type are not broadly new. Certain of them have small slots which take the place of the loop and on applying or removing these garters with the small slots, considerable difficulty is experienced in passing the clasp end into and out of the slot. On the other hand, the large loop 12 presents no difficulty of this kind. In other forms there is a positive fastening means at the end of the loop where the body portion passes therethrough. In the present instance there is no such fastening means, since none is necessary, the whole adjustment being effected in the present instance, as stated before, by adjusting the size of the loop.

In Figure 6, I have shown a modified form of the device in which the body portion 1 has two straps 3^a and 3^b holding two clasps 4^a and 4^b respectively, for the purpose of allowing two attachments to the sock when that is desired. In this form of the device one of the straps 3^a or 3^b is passed through the loop 12 (the particular strap passing through the loop depending upon whether the garter is being worn upon the right leg or the left leg) while the other strap does not pass through the loop, but extends directly downwardly from the garter to the sock. In both of these forms the operation of adjusting the garter is precisely the same, the only difference being the extra support.

I claim:

1. A washable garter comprising a resili-

ent fabric body portion having reenforced ends, a clasp member secured to one of said reenforced ends, a pair of slots carried by the other reenforced end and extending transversely of the longitudinal axis of the garter, said last named slots being arranged to receive the body portion whereby a loop is formed, a slidable stop member for determining the size of the loop, the end of the garter bearing the clasp being adapted to pass through said loop.

2. A washable garter comprising a resili-
ent fabric body portion, a clasp member secured to one end of said body portion, said body portion being provided with a pair of slots near the opposite end extending transversely of the longitudinal axis of the garter, said slots being arranged to receive the end of the body portion bearing the clasp, whereby a loop is formed, and a slid-
able stop member for regulating the size of the loop.

3. A washable garter comprising a resili-
ent fabric body portion, a clasp member se-
cured to one end of said body portion, said body portion being provided with a pair of slots near the opposite end extending trans-
versely of the longitudinal axis of the gar-
ter, said slots being arranged to receive the end of the body portion bearing the clasp,
whereby a loop is formed, and a slid-
able stop member for regulating the size of the loop, said stop member having a portion
arranged to extend over one of said slots
when the garter is in use.

EDWARD CHARLES BLOMEYER.
